UNITED STATES PATENT OFFICE.

MILLARD L. HARVEY, OF SAVANNAH, GEORGIA, ASSIGNOR OF ONE-FOURTH TO HERMAN ROSENHEIM, ONE-FOURTH TO GIRARD M. COHEN, AND ONE-FOURTH TO JOHN M. MIDDLETON, ALL OF SAVANNAH, GEORGIA.

SWITCH-LOCK.

1,285,151.

Specification of Letters Patent. Patented Nov. 19, 1918.

Application filed February 21, 1916. Serial No. 79,733.

To all whom it may concern:

Be it known that I, MILLARD L. HARVEY, a citizen of the United States, residing at Savannah, in the county of Chatham and State of Georgia, have invented certain new and useful Improvements in Switch-Locks, of which the following is a specification.

My invention aims to provide a simple and efficient lock for holding the switch points or tongues in the position which they assume when the main line is in use and to this end the novel construction hereinafter fully described and claimed is provided, this construction being shown in the accompanying drawing which constitutes a part of this specification and in which:

Figure 1 is a plan view of the device applied showing the same in operative position;

Fig. 2 is a similar view with the switch open;

Fig. 3 is a longitudinal section on the plane of the line 3—3 of Fig. 2;

Fig. 4 is an enlarged top plan view of the parts seen in Fig. 3;

Fig. 5 is a vertical transverse section on the plane of the line 5—5 of Fig. 1; and,

Fig. 6 is a sectional view on the plane indicated by the line 6—6 of Fig. 5.

Fig. 7, is a detail sectional view showing the manner in which one of the journals of the locking plate is connected to its operating shaft;

Fig. 8 is an enlarged vertical section on the planes indicated by the line 8—8 of Fig. 4; and

Fig. 9 is a horizontal section on the plane designated by the line 9—9 of Fig. 8.

Throughout the several views the numerals 1 designate a pair of switch tongues, 2 indicates the bridle bar connecting them, 3 has reference to the usual switch stand into which said bridle bar extends, 4 designates the rock shaft for operating the mechanism within the stand 3 for shifting the bridle bar 2, and 5 refers to the switch lever secured on said rock shaft for turning the same at will.

A flat locking plate 6 extends transversely between the line rails 7 and is provided at its ends with journals 8 which are mounted rockably in openings formed through the webs of the rails 7 and in other openings in bearing plates 9 secured to said webs as

shown in Figs. 5 and 6. The journals 8 preferably though not necessarily extend from the plate 6 in line with one edge thereof while the other edge of said plate is formed with a pair of notches 10 adapted to receive the free ends of the switch points 6 or tongues 1 when the switch is closed to permit free use of the main line. Under the present invention, the plate 6 is automatically moved to this position (see Fig. 1) when the lever 5 is swung in one direction 65 to close the switch, and when said lever is reversed to change the position of the tongues 1, the plate in question will be moved to a reverse position as indicated in Fig. 2. These results are attained by the 70 operating connections now to be described.

A shaft 11 extends from one of the journals 8 and is secured thereto by an appropriate coupling 12, the outer end of said shaft being mounted in a bearing bracket 13 75 which rises from a base 14. Said outer end of the shaft 11 carries a pinion 15 meshing with rack teeth 16 on the lower side of one end of a bar 17 which extends parallel with the rails, the other end of said bar having 80 teeth 18 meshing with a pinion 19 on the rock shaft 4. As shown clearly in Figs. 3 and 4, the bar 17 is slidably mounted in bearing brackets 20 rising from the base 14.

By the construction shown and described, 85 turning of the shaft 4 will similarly turn the shaft 11 and due to the provision of the pinions 15 and 19 and the bar 17, it will be obvious that turning of said shaft will move the locking plate 6 from one position to the 90 other according to the direction in which the lever 5 is thrown.

It is obvious that sufficient lost motion must occur to permit the locking plate 6 to move to inoperative position before the 95 switch tongues 1 start upon their opening movement, and although this could be accomplished in a number of ways, the following construction is preferably used (see Figs. 8 and 9).

The bridle bar 2 is provided with an elastic section 25 located preferably in the switch stand 3, and the inner end of said bar is forked and provided with a pin 26 which is received in an arcuate slot 27 105 formed in a disk 48 which is located in the stand 3 and secured to the vertical shaft 29 which rises through said stand and carries

the usual signal 30. A bevel gear 31 is secured on the shaft 29 and meshes with a pinion 32 on the inner end of shaft 4, said pinion being half the size of said gear.

5 By the construction described, turning of the lever 5 from the position of Fig. 1 will produce the following movements:

Shaft 4 shifts the rack bar 17 so as to turn shaft 11 to raise the locking plate 6 from operative position, and while this is taking place, shaft 4 and the gearing 31-32 turn shaft 29, but due to the pin and slot connection 26-27, turning of said shaft 29 does not affect the bridle bar 2 until the 15 locking plate 6 has raised sufficiently to permit the points 1 to move. By the time this position of the locking plate has been reached, however, one end of the slot 27 strikes pin 26, so that the continued movement of the shaft 29 will shift the bridle bar 2 to open the switch as shown in Fig. 2. During this movement of bar 2, the 20 elastic section 25 thereof does not come into play, but acts when the switch is being again closed.

When the switch stands open, the several parts are positioned as shown in Figs. 2, 3, 4, 8 and 9. To now close the switch, the lever 5 is swung to the right (Fig. 4.) This 30 movement causes rack bar 17 to start moving, the locking plate to operative position and at the same time, the shaft 29 and its disk 28 start shifting the bridle bar to move the switch tongues to the position of Fig. 35 1, said disk now turning in the direction of the arrow of Fig. 9. The right hand tongue 1 (Figs. 1 and 2) strikes the main track rail about the time that the locking plate 6 reaches the dotted line position of Fig. 6 and since the major portion of the 40 bridle bar 2 can then move no farther, the elastic section 25 thereof comes into play to permit the continued operation required to move plate 6 to its operative position 45 (Figs. 1 and 6).

From the foregoing description taken in

connection with the accompanying drawing, it will be observed that although the invention is of extremely simple and inexpensive nature, it will be highly efficient and durable. For these reasons, the construction shown and described constitutes the preferred embodiment of the lock but it is to be understood that within the scope of the invention as claimed, numerous changes 55 may be made without sacrificing the principal advantages.

I claim:

1. The combination with a pair of switch tongues, a pair of line rails with which the same coöperate, and means for shifting said tongues including a rock shaft; of a second rock shaft parallel to the first, a vertically swinging lock plate to which said second shaft is connected, said lock plate co-operating with the switch tongues to hold them against movement, pinions on the two rock shafts, and a bar extending transversely of said shafts and having teeth meshing with said pinions. 70

2. The combination with a pair of switch tongues, a pair of line rails with which they coöperate, and means for operating said tongues including a rock shaft; of a tongue locking plate extending transversely between said line rails at the free ends of the tongues and having notches in one edge adapted to receive said ends to hold them in one position, rotatably mounted journals projecting from the ends of the locking 80 plate, one of said journals being extended in the form of a rock shaft, pinions on the two rock shafts, a bar extending transversely of said shafts and having teeth meshing with both pinions, and means for 85 slidably supporting said bar.

In testimony whereof I affix my signature in the presence of two witnesses.

MILLARD L. HARVEY.
